[57] CLAIM

The ornamental design for an elevated multiple dome
funeral mausoleum, as shown.

DESCRIPTION

FIG. 1 is a perspective view of a multiple elevated
funeral dome for four corpses, showing my new design;
FIG. 2 is a top plan view thereof;
FIG. 3 is a right side elevational view thereof; and
FIG. 4 is a left side elevational view thereof.

FIG. 4

FIG. 3
